UNITED STATES PATENT OFFICE

172,570

FORK OR THE LIKE

John O. Van Koert, New York, N. Y.

Application May 27, 1953, Serial No. 25,215

Term of patent 14 years

(Cl. D54—12)

To all whom it may concern:

Be it known that I, John O. Van Koert, a citizen of the United States of America, residing at New York, county of New York, and State of New York, have invented a new, original, and ornamental Design for a Fork or the like, of which the following is a description, reference being had to the accompanying drawings, forming a part thereof.

Fig. 1 is a plan view of a fork showing my new design;

Fig. 2 is a side view of the fork shown in Fig. 1;

Fig. 3 is a vertical section taken on the line 3—3 of Fig. 1;

Fig. 4 is a vertical section taken on the line 4—4 of Fig. 1;

Fig. 5 is a vertical section taken on the line 5—5 of Fig. 1; and

Fig. 6 is a vertical section taken on the line 6—6 of Fig. 1.

The back of the fork is plain as indicated by Figs. 2—6 inclusive.

While the ornamental design as illustrated herein is shown applied to a fork, it is to be understood that the design is also intended for use on knives, spoons, or other suitable articles of flatware.

I claim:

The ornamental design for a fork or the like, substantially as shown.
